UNITED STATES PATENT OFFICE.

CHARLES L. THOMAS, OF JAMESVILLE, WISCONSIN.

VEHICLE-SPRING.

SPECIFICATION forming part of Letters Patent No. 258,823, dated May 30, 1882.

Application filed November 26, 1881. (Model.)

To all whom it may concern:

Be it known that I, CHARLES L. THOMAS, a citizen of the United States, resident of Janesville, in the county of Rock and State of Wisconsin, have invented a new and valuable Improvement in Wagon-Springs; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a bottom view of my invention. Fig. 2 is a cross-section, and Fig. 3 is a perspective detail.

This invention has relation to the spring connections between the bars of the running-gear and the body of the wagon; and it consists in the construction and novel arrangement of the two-branched spiral springs, having end arms secured to the body-sills and the pivoted arms extending inward from the side bars and connected to the springs between the branches, as hereinafter set forth, and especially pointed out in the claims appended.

In the accompanying drawings, the letter A designates the side bars of the wagon, and B the body-sills or bottom framing of the body.

C indicates the two-branched spiral springs, of which four are usually employed, attached near the ends of the body on opposite sides thereof. Each spring C consists of two spiral branches, D D, each having an end arm, a, extending outward from the spiral to the marginal frame-work B of the body, and secured thereto by means of a screw or bolt, b, passing through a terminal eye, c. These arms a extend inward from the sills B, so that the springs are under the body, the spiral branches being turned downward or below the plane of the arms a, as indicated in the drawings. The spiral branches D D extend toward each other horizontally, and are connected by or provided with central arms, d, extending from the lower portions of the inner coils, e. The arms d are flattened or squared, and are rigidly secured, by means of wedges g or other common fastenings, in seats h, made transversely and horizontally in the inner ends of the pivoted

arms E. The arms E serve to connect the springs to the side bars and support the body. They are made of metal, and are pivoted to hangers k, secured to the side bars by means of pivot-bolts l. Each arm is connected to a spring, C, between its spiral branches, as above set forth. The arms connected to the front springs are usually provided with outward extensions m beyond the side bars, supporting steps n. The branch spirals of the springs C are on each side of the arm E, and each spiral is secured to the body at the outer end or arm, a. In this manner it is designed to avoid end pitch. As the spring is free from any bearing in connection with the body in its middle portion, it gives inward readily as the arm E comes down under pressure. The arrangement of the springs well under the body of the wagon puts them practically out of sight.

A spring for buggies, seats, &c., consisting of a single perpendicular coil formed near the center of a bar or rod of steel, the two projecting ends of which, extending in the same direction, form an upper arm, (the end of which is shaped at an angle into a rest for the box or seat,) and a lower arm, longer than the upper arm and bent near the end to a perpendicular elbow, and upon the end having ears for attachment to the clip-ties, is not new.

A vertical standard secured to the side bar of a vehicle has been surrounded by a coiled spring resting on a shoulder at the bottom of the same, and a thimble which rests over the standard and incloses the spring has been provided with a lug, to which a horizontal arm having a transverse thimble at its outer end has been pivoted, has been used in connection with two coiled springs on a shaft, one on each side of the transverse thimble, their inner ends being connected to the transverse thimble and their outer ends to lugs or plates, which hold the shaft and prevent it from turning. This construction is not claimed herein, and protection only is asked for what is hereinafter claimed.

Having described this invention, what I claim, and desire to secure by Letters Patent, is—

The springs C, each consisting of the two spiral branches D D, each having an end arm, a, extending outward from the spiral to the

marginal frame-work B of the body, and secured thereto by means of the screw or bolt *b* passing through a terminal eye, *c*, in combination with the arms E, pivoted to hangers on the side bars, extending inward, and secured to the springs C upon arms *d* between the spiral branches D D, substantially as specified.

In testimony that I claim the above I have hereunto subscribed my name in the presence of two witnesses.

CHARLES LEE THOMAS.
